MULTIPLE SOCKET FLEXIBLE LAMP
FIXTURE

William E. Montague, Inglewood, Calif.

Application February 24, 1950, Serial No. 146,111

2 Claims. (Cl. 240—81)

1

This invention relates to a novel construction of lamp fixture and more particularly to a novel adjustable lamp bulb supporting means for various types of lamps, such as floor lamps, table lamps and desk lamps.

Among the primary objects of the present invention is to provide a unit whereby a conventional electric lamp may be readily converted from a rigid lamp bulb supporting structure to a flexible or adjustable structure to enable the lamp bulbs and their supporting sockets to be moved to different positions to obtain maximum utilization of the light rays from each bulb and for directing the light rays to a position where the rays are primarily required, thus providing better illumination without an increase in the amount of candle power utilized.

Still a further object of the invention is to provide a flexible lamp bulb supporting structure whereby light bulbs of greater length or size may be employed with a lamp shade of a particular size and which also enables the use of shallower lamp shades as well as lamp shades of smaller diameter with lamp bulbs of a given size.

Numerous other objects and advantages of the invention will hereinafter become more fully apparent from the following description of the drawings, illustrating a presently preferred embodiment thereof, and wherein:

Figure 1 is a side elevational view, partly in vertical section of a floor lamp shown equipped with the invention;

Figure 2 is an enlarged fragmentary side elevational view of the upper portion of the floor lamp, with the shade omitted and illustrating the invention more in detail;

Figure 3 is a side elevational view, partly in vertical section looking from right to left of Figure 2;

Figure 4 is a top plan view of the parts as seen in Figure 2;

Figure 5 is a fragmentary vertical sectional view taken substantially along a plane as indicated by the line 5—5 of Figure 4;

Figure 6 is a horizontal sectional view taken substantially along a plane as indicated by the line 6—6 of Figure 5, and

Figure 7 is an exploded perspective view of certain of the parts of the invention.

Referring more specifically to the drawings, for the purpose of illustrating the flexible lamp bulb mounting unit, designated generally 8 and comprising the invention, one form of lamp has been illustrated in Figure 1 and designated

2

generally 9, said lamp being of the type commonly known as a "floor lamp." The lamp 9 includes a base 10 which may be of any desired construction and which supports an upstanding tubular standard 11, the bore of which forms a conduit for electrical conductors, as is conventional.

The upper end portion of the standard 11 is modified as best illustrated in Figure 5 by being provided with an annular flange 12, constituting a part of the flexible lamp bulb mounting 8 and which annular flange 12 extends outwardly from the standard 11 and is provided with an annular or endless upstanding flange portion 13.

The standard 11 above the flange 12 is provided with diametrically opposed openings 14 and thereabove said standard has a closed end 15 provided with a restricted upstanding threaded shank 16 which is adapted to be threadedly engaged in a downwardly opening threaded recess 17a of the usual lamp shade frame retaining knob 17. A cap 18 is provided with a central opening 19 in its top wall which loosely engages the threaded shank 16 and is provided with a depending annular wall 20 the bottom edge of which rests upon the upper edge of the flange portion 13, which flange supports the cap 18 on the standard 11. The usual lamp shade supporting frame 21 is detachably supported on the cap 18 at its center and detachably secured thereto by the knob 17. The frame 21 supports a lamp shade 22 of any conventional construction which is disposed around the upper portion 35 of the standard 11 and accordingly around the flexible mounting unit 8. The parts 10, 17, 21 and 22 and the portion of the standard 11 located below the flange 12 constitute no part of the present invention and may obviously be varied at will, as will hereinafter become apparent.

The flexible mounting unit 8 includes a pair of tubes 23 having corresponding, inner ends secured in openings 24 of the flange 13 and which are disposed substantially tangentially of the standard 11 and parallel to one another. Each tube 23 supports a connecting member or block 25 having a bore 26 adjacent its upper end which is secured by a press fit engagement on the outer end of its supporting tube 23 and which is provided adjacent its lower end with a bore 27 which is disposed at a right angle to the bore 26. A bolt, designated generally 28 is detachably and adjustably supported by each connect-

ing member 25 and includes a shank 29 having an eye 30 at one end thereof and which is enlarged relatively to the shank 29. The shank 29 is provided intermediate of its ends with an enlargement 31 and is externally threaded as seen at 32 at its opposite end and is provided with a longitudinally extending slot 33 in its threaded portion 32, as best illustrated in Figure 7; however, a longitudinal groove may be substituted for the slot 33, as will hereinafter become apparent. The threaded shank end 32 extends loosely through the bore 26 and the enlargement 31 bears against the outer side of the connecting member 25. A washer 34 is slidably mounted on the threaded shank end 32 and bears against the inner side of the connecting member and is provided with a lug 35 which extends into the opening thereof and which engages the slot 33 for nonrotatably mounting the washer 34 on the shank end 32. A thumb nut 36 threadedly engages said shank end 32 for detachably connecting the bolt 28 to the connecting block 25.

A conventional lamp socket 37 is supported by each bolt 28 by a press fit engagement of the restricted nipple 38, at the base end thereof, in the eye 30 of said bolt. Each lamp socket 37 mounts a conventional lamp bulb 39. Each lamp socket 37 has two electrical conductors not shown, connected thereto in a conventional manner and which are contained within a flexible cable or housing of an insulating material which extends from the base end 38 of the lamp socket through the tube 23, which supports said socket 37, through an opening 14 which is located adjacent the inner end of said tube 23 and thence longitudinally downwardly through the standard 11. The two flexible cables 40 may merge within the standard 11 and are adapted to be provided at their opposite ends with a conventional plug, not shown, for connection to a source of electric current such as an outlet box, not shown. Likewise, the lamp 9 may be provided with a switch interposed at any point in the electric circuit thereof and which is likewise not shown.

The knurled thumb nuts 36 are tightened sufficiently so that the enlargements 31 and washers 34 will frictionally engage the connector blocks 25 with sufficient gripping engagement to retain the sockets 37 in any position to which they may be moved but sufficiently loose so that the bolts 28 may be turned in the bores 27 to swing the lamp sockets 37 from their horizontal to their vertical positions, as illustrated in Figure 1 or to any angle therebetween and so that the lamp sockets and the bulbs supported thereby will remain in any position to which they are moved. The washers 34 are provided to turn with the bolts 28 so that the thumb nuts 36 will not become loosened by frictional contact with a part, relative to which the bolt is turned.

From the foregoing it will be readily apparent that the sockets 37 and bulbs 39 may be adjustably positioned relatively to one another and to the standard 11 for concentrating the light rays from both bulbs in any desired direction to obtain maximum utilization of the light provided. It will likewise be readily apparent that by adjustment of the sockets 37, larger or longer lamp bulbs may be used without such bulbs extending below the shade 22 and through the utilization of

the flexible mounting 8, lamp shades of a smaller diameter and of a reduced depth may be utilized with lamp bulbs of any given size.

Obviously, the mounting 8 could be provided for a single socket and lamp bulb or for more than two sockets and lamp bulbs by varying the circumferential spacing of the tubes 23. As previously mentioned, the flexible mounting unit 8 may be employed with any type of electric lamp and various other modifications and changes are likewise contemplated and may obviously be resorted to, without departing from the spirit or scope of the invention as hereinafter defined by the appended claims.

15 I claim as my invention:

1. A flexible light source mounting for electric lamps comprising, in combination with an electric lamp including a base, a standard, a lamp shade and a lamp shade supporting frame; a tubular supporting member, means to support said tubular supporting member at one of its ends on the standard at an angle to the axis of the standard, a connector member having one end connected to the opposite end of said tubular supporting member and having a depending portion defining its opposite end provided with a bore disposed at a right angle to the axis of the tubular supporting member, and a bolt having a shank portion loosely engaging the bore of said connector member and rotatably connected thereto, said bolt having an eye at one end thereof offset laterally relatively to the supporting member in a direction away from the standard and adapted to receive therein a base end of a lamp socket for supporting the lamp socket on the bolt with the axis of the lamp socket at a right angle to the axis of the connector member bore and bolt for adjustably mounting a lamp bulb, connected to the lamp socket, relatively to said standard for swinging movement of the bulb and socket in a vertical plane parallel to and laterally spaced from the vertical plane of the supporting member.

2. A flexible light source mounting as in claim 1, and a second tubular supporting member, connector member and bolt supported by said lamp standard for adjustably mounting a second lamp socket and lamp bulb, said tubular supports being disposed substantially parallel to one another and being offset outwardly in opposite directions relatively to the axis of the lamp standard, and the lamp sockets being supported outwardly with respect to remote sides of the supporting members by the bolt eyes.

WILLIAM E. MONTAGUE.
